UNITED STATES PATENT OFFICE.

SPENCER OTIS, OF CHICAGO, ILLINOIS, ASSIGNOR TO NATIONAL DUMP CAR COMPANY, A CORPORATION OF MAINE.

CAR.

No. 854,701.

Specification of Letters Patent.

Patented May 21, 1907.

Application filed October 4, 1906. Serial No. 337,448.

To all whom it may concern:

Be it known that I, SPENCER OTIS, a citizen of the United States, residing at Chicago, in the county of Cook and State of Illinois, have invented certain new and useful Improvements in Cars, of which the following is a specification.

My invention relates to improvements in cars, and particularly to the means for opening and closing the dumping doors in the base of so-called dump cars.

My invention is an improvement upon cars of this class; and has for its specific object the provision of more simple and durable means for rotating the shaft which bears against the doors to close them and to secure them in their closed position.

My invention is illustrated in the accompanying drawings, in which—

20 Figure 1 is an end elevation of a car provided with my improvements. Fig. 2 is a detail sectional elevation of one of the ratchet devices shown in Fig. 1. Fig. 3 is a section taken on line 3 of Fig. 2. Fig. 4 is a section 25 taken on line 4 of Fig. 2.

Referring to the drawings, *a* represents the end of a car resting upon the end sill *b*, which may be of wood or metal. Immediately below the end sill and secured thereto are the 30 slanting racks *c* having teeth *c'* thereon and arranged to guide the toothed rollers *d* in such manner as to bring the shaft *d'*, upon which such rollers are mounted, into registry with the cams *e*, which are secured to the 35 doors *f*, so that when the roller and shaft are in the position shown on the left-hand side the cam will rest with its flat portion *e'* upon the shaft and the door will be securely held in its horizontal closed position. This shaft 40 *d'* extends the entire length of the car and may be supported at several points throughout its length by racks and braces similar to *c*, a cog being placed upon the shaft to register with each of the braces.

45 In order to move the shaft from the position shown at the left of Fig. 1 to the position shown at the right of Fig. 1, I have provided a sprocket wheel *g* secured to the shaft and around which the chain *h* extends to a 50 sprocket wheel *i*, which is adapted to be rotated by means of the handle *j*. In order to maintain the two sprocket wheels always at the same distance apart, I have provided the metal link *k*, through the lower end of which

the shaft *d'* extends and to the upper end of which is secured the fork *k'* which forms a portion of the bearing for the upper sprocket shaft *l*. It is convenient in rotating this upper sprocket wheel to oscillate the handle *j* rather than give it complete revolutions, and in order that motion may thus be transmitted to the sprocket wheel I have provided two ratchet wheels *m* and *n* and two reversible ratchet pawls *m'* and *n'*, the former being pivoted between forks *j'* and *j''* upon the handle and being provided with the spring *m''* which holds the pawl in either of its two positions against the ratchet wheel; and the latter ratchet pawl *n'* being pivoted upon the upper end of the link *k*, such that it can be thrown either to the right or to the left to prevent the sprocket wheel from turning backward when the back stroke of the handle is being made.

It will be noted that the shaft *d'* describes 75 a substantially straight path in passing from one end to the other of the rack *c*, and therefore the upper end of the link *k* cannot be simply pivoted but must be secured to the end *a* of the car in such manner as to allow 80 sufficient vertical motion to compensate for the difference in distance between the shaft *d'* and the original position of the upper sprocket. Through the end *a* of the car is placed a thimble *a'*, this thimble being provided with a longitudinal slot *a''*, through 85 which the end of the upper sprocket shaft extends. Upon the end of the shaft *l*, the nut *o*, having a flange large enough to cover the slot *a''*, is threaded, and in order to prevent 90 its becoming loosened the pin *o'* is passed through the nut and the threaded end of the shaft. Against the outside of the slot *a''* the flanged portion *l'* of the shaft *l* rests, and together with the nut *o* prevents dirt from getting into the slot.—The sprocket wheel *i* and large ratchet *n* are likewise secured to the shaft by the pin *d'*, while the small ratchet *m* is formed with a square opening and fitted to a square portion of shaft *l*. The nut *o''* is 100 threaded upon the projecting end of shaft *l* to hold the handle *j* and small ratchet in place, and is likewise prevented from turning by a pin *o''*.

In operation, supposing the door to be 10; originally closed as shown on the left of Fig. 1, the ratchet pawl *m'* is thrown so that the oscillation of the handle *j* causes a clockwise

rotation of the upper sprocket, the rotation of the upper sprocket imparting a similar clockwise rotation to the lower sprocket and thereby to the lower shaft and pinions secured thereon and moves the shaft as a whole down the incline of the rack *c*. This allows the door *f* to swing downward upon its hinges, the cam *e* following in contact with the shaft. When it is desired to again close the doors, the position of the ratchet pawl *m'* is reversed and the pawl *n'* is thrown into the position shown on the left of Fig. 1, so that as the handle is oscillated to rotate the upper sprocket in a counter clockwise direction the ratchet pawl *m'* will catch upon the ratchet teeth *n* and prevent the shaft from moving under the weight of the door while the back stroke of the handle is being made.

While I have here described and shown certain details of my invention, it is to be understood that I do not wish to be unduly limited thereto, it being possible to provide details of other form without departing from the spirit or scope of my invention.

I claim:

1. In a car of the class described, the combination of a frame, a hinged dumping door forming a part of the bottom of the car, a reciprocating shaft beneath the door and operatively connected therewith, and driving mechanism connected at one end to the reciprocating shaft and at its opposite end in sliding engagement with the end of the car.

2. In a car of the class described, the combination of a frame, a hinged dumping door

forming a part of the bottom of the car, a reciprocating shaft beneath the door and operatively connected therewith, a link having its lower end movable with the shaft and having its upper end in sliding engagement with the end of the car, and driving means carried by the link.

3. In a car of the class described, the combination of a frame, a hinged dumping door forming a part of the bottom of the car, a reciprocating shaft beneath the door and operatively connected therewith, a track upon which the shaft is supported, a sprocket wheel on the shaft, a sprocket wheel mounted upon the end of the car, a rigid link connecting the sprocket wheels, a chain passing around the sprocket wheels, and an operating device for the chain and sprocket mechanism.

4. In a car of the class described, the combination of a frame, a hinged dumping door forming a part of the bottom of the car, a reciprocating shaft beneath the door and operatively connected therewith, a sprocket wheel upon this shaft, an operating shaft in sliding engagement with the end of the car, a sprocket wheel on the operating shaft, a rigid link connecting the shafts, a detent mechanism for the operating shaft, a chain, and an operating handle on the operating shaft.

SPENCER OTIS.
